United States Patent Office

Des. 191,355
Patented Sept. 19, 1961

191,355

CHAIR

Nathan Sussman, 69 2nd Ave., Brooklyn, N.Y.

Filed Dec. 19, 1960, Ser. No. 63,253

Term of patent 3½ years

(Cl. D15—1)

FIG. 1 is a side view of the chair, showing my new design.

FIG. 2 is a front elevational view of the chair.

FIG. 3 is a front perspective view thereof.

The back of the chair is substantially the same in appearance as the front thereof.

I claim:

The ornamental design for a chair, as shown and described.
